UNITED STATES PATENT OFFICE.

THOMAS F. TIERNEY, OF NEW YORK, N. Y.

DESIGN FOR A CHURN-DASHER.

SPECIFICATION forming part of Design No. 33,505, dated November 6, 1900.

Application filed May 8, 1900. Serial No. 15,984. Term of patent 14 years.

To all whom it may concern:

Be it known that I, THOMAS F. TIERNEY, a citizen of the United States, residing in the city of New York, in the county and State of New York, have invented and produced a new and original Design for a Churn-Dasher, of which the following is a specification, reference being had to the accompanying drawings, forming a part hereof, and wherein—

10 Figure 1 is a perspective view in elevation of a churn-dasher, showing my new design. Fig. 2 is a bottom end view thereof.

15 As shown in the drawings, the leading or material features of my design consist of a circular disk or body A, with vertical plain perimetral face, having a circular depression 1 and opening 2 and conical top B, from the

frustum of which is produced a vertical stem C, with curved swell *a* at the base and flaring from the curved base portion to the top, terminating in an annular reduced portion *b*, within straight lines, as shown.

Having thus described my invention, what I claim is—

The design for a churn-dasher as herein shown and described.

In testimony whereof I have hereunto set my name to this specification in the presence of two subscribing witnesses.

THOMAS F. TIERNEY.

Witnesses:

WALLACE MURDOCK,
C. G. HEYLMUN.
